UNITED STATES PATENT OFFICE.

LEVI M. BOWMAN AND WILLIAM A. SMITH, OF TULSA, OKLAHOMA.

ELECTRICAL GUN.

1,239,344.

Specification of Letters Patent.

Patented Sept. 4, 1917.

Application filed May 29, 1917. Serial No. 171,697.

To all whom it may concern:

Be it known that we, (1) LEVI M. BOWMAN, (2) WILLIAM A. SMITH, citizens of the United States, residing at Tulsa, in the 5 county of Tulsa and State of Oklahoma, have invented certain new and useful Improvements in Electrical Guns; and we do hereby declare the following to be a full, clear, and exact description of the invention, such as will enable others skilled in the art to which it appertains to make and use the same.

This invention relates to electrical guns, and the primary object of the invention is 15 to provide a gun which may be made safe from accidental discharge, and after having once been sighted, the pulling of the trigger to fire the gun will not pull the gun off from the object sighted at.

20 Another object of the invention is to provide an electrical gun structure including a primer or firing cap, which carries a sparking point, so that the shell is discharged by the formation of a spark in the primer, 25 thereby eliminating the liability of accidental discharge of a shell, by a blow or jolt.

With the foregoing and other objects in 30 view, this invention consists in such novel features of construction, combination and arrangement of parts as will be hereinafter more fully described, illustrated in the accompanying drawings and claimed.

In describing the invention in detail, reference will be had to the accompanying drawings wherein like characters designate 35 like and corresponding parts throughout the several views, and in which:—

Figure 1 is a longitudinal section through 40 the improved gun;

Fig. 2 is an enlarged fragmentary section through the gun; and

Fig. 3 is a detailed section through the primer.

45 Referring more particularly to the drawings, 1 designates the gun barrel, and 2 the gun stock. The barrel 1 is connected to the gun stock in the usual manner of the connection of shot gun barrels to the stocks so that 50 the barrel may be swung, by the actuation of the lever 3 for placing an unexploded shell within the breech of the barrel 1.

The stock 2 of the gun has a battery 5 mounted therein which is connected to an 55 induction coil or transformer 6, by a wire conductor shown at 7. The battery 5 is also

connected by a wire 8, to one end of an adjustable contact member 9 as clearly shown at 10 in Fig. 2 of the drawings. The adjustable contact member 9 is carried by a 60 block 11 of insulation, and it has a platinum contact 12 formed upon its inner end which is adapted for engagement with a platinum contact 13 carried by a pin 14. The pin 14 is pivotally connected as shown at 15 to the 65 trigger 16 of the gun. The trigger 16 of the gun is pivotally mounted on a pin 17 so that when the trigger is moved rearwardly the contact 13 will be forced into engagement with the contact 12 for closing an electrical 70 circuit, to discharge a shell, indicated at 18, as will be hereinafter more fully described. The trigger 16 has a spring 19 connected thereto which is also connected to a pivotally mounted finger 20. The finger 20 is 75 pivotally mounted as shown at 21 and it is guided, in its pivotal movement by a guide 22. The primary circuit of the induction coil 6 is grounded through a wire 20, as shown at 21, so that when the contact 13 is 80 moved into engagement with the contact 12, the circuit will pass through the battery 5, wire 7, induction coil 6, upwardly through the trigger 16, pin 14, contacts 12 and 13, through the contact member 9 and wire 8 85 back to the battery 5.

The shell 18 has a primer 25 mounted therein, as is usual in shot gun shell construction, which primer is composed of an outer shell 26 in which is mounted a plug 90 27. The plug 27 is constructed of insulating material and an electrode 28 extends centrally therethrough, and projects a short distance out of the inner end of the plug 27 as clearly shown in Figs. 2 and 3 of the drawing. The inner end of the casing 26 is bent over the end of the insulating plug 27 as shown at 29 and the ends and the protruding end of the electrode 28 engage the charge 30 of the shell 18. The secondary coil of 100 the transformer or induction coil 6 passes through wires 31 and 32, which are heavily insulated as indicated at 33, to the breech of the gun barrel. The wire 32 engages the central electrode 28, while the wire 105 32 engages the shell or casing 26 of the primer, so that when the primary circuit is closed by the operation of the trigger 16, the secondary current will flow through the wires 31 and 32 into the electrode 28 and 110 the casing 26 of the primer causing a spark to jump from the protruding end of the

electrode 28 to the inwardly curved end 29 of the shell 26 of the primer 25 which will explode the powder charge 30 of the shell 18.

5 A safety switch indicated at 34 is interposed in the wire 8 so that when it is desired this switch may be opened for preventing accidental discharge of the gun.

10 A second safety arrangement is provided, which may be quickly and easily operated by the gunner, when it is desired to discharge the gun. The second safety arrangement comprises a trigger 35 which is pivotally mounted as shown at 36 within the trigger guard 37, and directly in front of the 15 trigger 16. A bar 38 is connected to the trigger 35 and it has an insulating plug 39 pivotally connected thereto as shown at 40 and extending upwardly therefrom. The insulating block 39 is forced, by the action 20 of the trigger 35 upwardly between the contacts 12 and 13 so as to prevent engagement between these members upon the operation of the trigger 16, thereby eliminating the accidental discharge of the gun when the 25 switch 34 is closed. When the switch 34 is closed, and also the safety plug 39 is positioned between the contacts 12 and 13, and the operator desires to discharge the gun, all that is necessary is to first operate the 30 trigger 35 for moving the insulating plug 39 downwardly from between the contacts 12 and 13, so that upon operation of the trigger 16 the contact 13 will be moved into engagement with the contact 12, for closing the circuit and discharging the gun as previously 35 described.

A branch wire 44 is connected to the wire 8, and to a wire 45, through a switch 46. The wire 45 extends along the gun structure, 40 at any convenient location, to the muzzle of the barrel, at which point it is connected to a light socket 47 which carries an ordinary incandescent light 48. The circuit is formed through the light 48, through the wire 44 45 and the gun barrel, with which the wire 20 is grounded, so that when it is desired to light the light 48, all that is necessary is to close the switch structure 46. This light may be utilized for "shining" the eyes of 50 various animals, such as coons, opossums, or the like, when hunting with the gun at night.

In reducing the invention to practice, certain minor features of construction, combination and arrangement of parts may necessitate alterations to which the patentee is entitled, provided such alterations are comprehended within the scope of what is claimed.

What is claimed is:—

60 1. In an electrical gun, the combination, with a gun stock, a gun barrel having a breech, of an electrical battery carried by said stock, an induction coil carried by the stock, a movable contact, a stationary contact, electrical conducting means connecting

said stationary contact to said battery, a conductor connecting said movable contact to said induction coil, means for moving said movable contact into engagement with said stationary contact for closing a circuit through said battery and coil, an insulating plug, and means for moving said insulating plug between said movable contact and said stationary contact for preventing the movable contact from being moved into engagement with the stationary contact. 75

2. In an electrical gun, the combination, with a gun stock, a gun barrel having a breech, of an electrical battery carried by said stock, an induction coil carried by the stock, a movable contact, a stationary contact, electrical conducting means connecting said stationary contact to said battery, a conductor connecting said movable contact to said induction coil, means for moving said movable contact into engagement with said stationary contact for closing a circuit through said battery and coil, an insulating plug, means for moving said insulating plug between said movable contact and said stationary contact for preventing the movable contact from being moved into engagement with the stationary contact, a shell primer having a metal casing, an insulating plug positioned in said casing, an electrode extending centrally through said plug, and conductors leading from said induction coil to said casing and electrode for causing a spark between the casing and electrode upon movement of said movable contact into engagement with said stationary contact, for exploding a shell in said gun barrel. 90

3. In an electrical gun, the combination with a gun stock, and a gun barrel having a breech, of an electrical battery carried by 105 said stock, an induction coil carried by the stock, a movable contact, a trigger connected to said movable contact for moving the same, a stationary contact, electrical conducting means connecting said stationary contact and said battery, electrical conducting means connecting said battery and said induction coil, electrical conducting means connecting said induction coil and said movable contact whereby a circuit will be closed through 110 said battery and coil upon pivotal movement of said trigger for moving said movable contact into engagement with said stationary contact, means for moving said movable contact out of engagement with the stationary contact upon release of said trigger, an insulating block, a trigger connected to said insulating block for moving the insulating block upwardly between said movable contact and said stationary contact for preventing the movable contact from being moved into engagement with the stationary contact. 115

4. In an electrical gun, the combination with a gun stock, and a gun barrel having a breech, of an electrical battery carried by 120

- said stock, an induction coil carried by the stock, a movable contact, a trigger connected to said movable contact for moving the same, a stationary contact, electrical conducting means connecting said stationary contact and said battery, electrical conducting means connecting said battery and said induction coil, electrical conducting means connecting said induction coil and said movable contact whereby a circuit will be closed through said battery and coil upon pivotal movement of said trigger for moving said movable contact into engagement with said stationary contact, means for moving said movable contact out of engagement with the stationary contact upon release of said trigger, an insulating block, a trigger connected to said insulating block for moving the insulating block upwardly between said movable contact and said stationary contact for preventing the movable contact from being moved into engagement with the stationary contact, a shell primer having a metal casing, an insulating plug positioned in said casing, an electrode extending centrally through said plug, conductors leading from said induction coil to said casing and electrode for causing a spark between the casing and electrode upon movement of said movable contact into engagement with said stationary contact, an incandescent light bulb carried by said barrel adjacent its muzzle, an electrical conductor connecting said incandescent light bulb to said battery, and a switch interposed in said last named conductor for controlling the ignition of the light by the current passing from said battery.
5. In an electrical gun, the combination with a gun stock, and a gun barrel having a breech, of an electrical battery carried by said stock, an induction coil carried by the stock, a movable contact, a trigger connected to said movable contact for moving the same, a stationary contact, electrical conducting means connecting said stationary contact
- and said battery, electrical conducting means connecting said battery and said induction coil, electrical conducting means connecting said induction coil and said movable contact whereby a circuit will be closed through said battery and coil upon pivotal movement of said trigger for moving said movable contact into engagement with said stationary contact, means for moving said movable contact out of engagement with the stationary contact upon release of said trigger, an insulating block, a trigger connected to said insulating block for moving the insulating block upwardly between said movable contact and said stationary contact for preventing the movable contact from being moved into engagement with the stationary contact, a shell primer having a metal casing, an insulating plug positioned in said casing, an electrode extending centrally through said plug, conductors leading from said induction coil to said casing and electrode for causing a spark between the casing and electrode upon movement of said movable contact into engagement with said stationary contact, an incandescent light bulb carried by said barrel adjacent its muzzle, an electrical conductor connecting said incandescent light bulb to said battery, and a switch interposed in said last named conductor for controlling the ignition of the light by the current passing from said battery.
